UNITED STATES PATENT OFFICE.

JAMES RANDOLPH GREENWOOD BRIERCLIFFE, OF MOSES GATE, BOLTON, ENGLAND.

YARN-TESTING MACHINE.

1,008,308.

Specification of Letters Patent. Patented Nov. 14, 1911.

Application filed November 6, 1909. Serial No. 526,647.

To all whom it may concern:

Be it known that I, JAMES RANDOLPH GREENWOOD BRIERCLIFFE, a subject of the King of Great Britain, and resident of 5 Lime Trees, Moses Gate, Bolton, in the county of Lancaster, England, have invented certain and useful Improvements in Yarn-Testing Machines, of which the following description, together with the accompanying sheets of drawings, is a specification.

My invention relates to a new or improved machine for automatically testing the strength and stretch of single strands or 15 threads of fibrous substances, such as cotton, worsted, linen, jute, and the like, which also includes partly prepared yarns such as those known in the condition of "rovings." To attain this object I make use of the de- 20 vices illustrated by the accompanying sheets of drawings, wherein:—

Figure 1 is a front elevation of the apparatus produced in accordance with my invention and shows it in position as 25 when testing a thread of yarn. Fig. 2 is an end elevation of same as seen in the direction indicated by the arrow *a*. Fig. 3 is a plan or view of the apparatus shown by Fig. 1, seen from above. Fig. 4 30 is a similar view to Fig. 1 but illustrates the relative positions of the several parts when the thread has broken under the test to which it has been put. Figs. 5, 6 and 7 are front and end elevations and plan respec- 35 tively of modifications hereinafter described.

In carrying my invention into effect I make use of a lever *b* of the first order the same being pivoted at 2, and having its arms 3 and 4 extending to the left and right of 40 said pivotal center 2. The bearings *c* upon which said lever is pivoted are fixed upon the base piece *d*, to which all the other fixings are secured as hereinafter explained, and said base piece *d* has loops or rings 5 and 6 secured to it so that it may be suspended or hung upon the wall, ceiling or the like, where it may be held at any desired height from the floor to suit the convenience of the user.

On the arm 4 of the lever *b* a runner *f* 50 is mounted so that it may revolve upon, or roll over the upper edge of said arm 4 and from this runner *f* the weight *g* is supported by a connecting rod *g*¹, so that as 55 said runner descends or travels over the arm 4 the weight *g* by gravity depresses it for

the purposes hereinafter explained. The other arm 3 of the lever *b* extends in the opposite direction so that by a fixing or clamping piece *h* secured thereon, threads of yarn as *k* that are to be tested may be secured thereto as well as secured to the clamping piece *h*¹ (which if desired may be of similar construction to that shown at *h*,) fixed upon the rigid arm *d*¹, said arm *d*¹ being fixed to the base piece *d*, and made to extend sufficiently for a given length of yarn to be stretched between the parts *h* and *h*¹.

At the extremity of the arm 3 a scale or graduated measure *m* is mounted on the base piece so that a pointer *3*^a on the end of said arm 3 may indicate as herein-after described. At the other end of the lever or at the outer extremity of its arm 4 is mounted a sliding or hinged piece *n* 70 carried within bearings *n*¹, and formed integrally with or connected to this sliding piece is a rod *n*² which is coupled to the arm *n*³ of the lever *n*⁴ which engages with the rod *n*⁵ (provided with a regulating nut *n*⁷) 80 to actuate the stop lever *n*⁶ arranged in connection with the apparatus for paying out what may be termed the governing cord which arrests the further movement of the runner *f* as hereinbefore explained.

As the weight *g* descends or as the runner *f* travels over the arm 4 by the action of gravity it carries with it the end of the cord *p* which encircles a grooved pulley or drum *p*¹ mounted upon bearings *q* secured 90 to the base piece *d*. This drum *p*¹ has mounted upon its axle a coiled spring *s* as well as the gearing wheel *p*², this latter being connected by a train of wheels *p*³ to the momentum governor *r* of well known construction. Upon the same base piece *d* a spring clip *t* is mounted within the grip of which may be placed the cop of yarn which has to be tested, or if it is yarn from the roving, then the same may be mounted as 100 shown in broken lines at *t*² so that said yarn may be carried therefrom to the part *h*¹, where it is secured, and forward to the part *h* as hereinbefore described.

In operation the runner *f* and its weight 105 *g* normally occupy the position indicated in Fig. 1, being held in that position by the cord *p* because rotation of drum *p*¹ is prevented by catch *q*². After the yarn *k* has been placed in position the catch *q*² is manually operated to release the drum *p*¹, whereupon the runner will descend the inclined

portion of lever arm 4, the speed of rotation of drum p^1 and consequently the speed of travel of said runner, being regulated by the governor r . As the runner progresses the lever arm 4 is depressed and this movement continues until the arm 3 of lever b has traversed a distance sufficient to stretch thread h to the breaking point, whereupon the lever arm 4 will immediately come in contact with the sliding piece n , and through the rod n^2 , lever arms n^3 and n^4 , and rod n^5 , cause the lever n^6 to move the catch piece q^2 so as to again engage with its wheel p^4 thus arresting the further movements of the train p^3 and consequently of the runner f and its weight g . The strain put upon the thread h is such as is indicated by the position that the pointer g^3 on the connecting rod g^1 shows on the scale u which is carried by the arm 4, and as will be understood this scale u is regulated in accordance with the actual weight of the weight g , that is to say, if the weight g is comparatively light then the scale u may be graduated to represent ounces, whereas if it is comparatively heavy then the scale u may be graduated to represent pounds, and the indicator at the end of the arm 3 may also be watched or noted as to the graduation that it was pointing at on the scale u at the time that the thread h was broken, and this will show the amount of stretch that was put upon said thread h before it was broken.

Provided it is not convenient to watch the pointer 3^a on the end of the arm 3, then I may have a glass or transparent tube v in which I place a transparent liquid as water, glycerin or the like, in which a small weight of substantially piston form may be allowed to descend, said weight being connected with its rod to the cord v^2 passed over the pulley v^3 to be connected to the end of the arm 3 so that on the thread h being broken the weight would indicate its position on the scale formed on the surface of the tube v and said weight will be held in the position it occupied on the breaking of the thread by the lever w^1 (pivoted at w^2) being moved by the part h^2 on the lever b so that the cord v^2 is clamped against the part w^3 .

To re-adjust the several parts to their positions as shown in Fig. 1 the user has to rotate the drum p^1 only, by the winged handle w .

Suitable stop pieces w^6 , w^7 are mounted on the casing q and the pulley respectively to arrest the motion of the said pulley p^4 in either direction so as to prevent overwinding or overrunning of the motor.

Should it be found that the testing of extremely delicate yarns is interfered with by the cord p being out of alinement with the center 2 of the lever b I mount the drum p^1 in the position as shown by Figs. 5, 6 and

7, then said cord p is always in alinement with the center 2 and the axis of the arm 4, thus the pull on the cord will always be against said center 2 and parallel with the axis of the arm 4. To effect this I mount upon the axle pin b^2 a guide pulley b^4 which will move with said axle pin b^2 and may freely revolve around its own center and in the plane of the center of said spindle b^2 . The cord p is connected to the cross-piece g^6 of the connecting rod g^1 , said cross-piece moving in the slot b^6 in the lever b .

Instead of arranging the pointer g^3 on the connecting rod g^1 , I may arrange such pointer g^3 to be carried by a pulley g^4 mounted on a spindle in bearings g^5 loosely pivoted on the pin f^1 which supports the runner f (see dotted lines Fig. 5) thus the position of said pointer g^3 relatively with the scale u is not affected by any oscillatory movements of the connecting rod g^1 .

Such being the nature and object of my said invention, what I claim is:—

1. In a machine for testing yarns, a support, a lever pivotally mounted in said support and having an inclined arm, means carried by said lever for securing one end of the yarn to be tested, means for securing the yarn at a fixed point, a weighted runner mounted to travel by gravity down the inclined arm of said lever, and means for controlling the speed and distance traveled by said runner.

2. In a machine for testing yarns, a support, a lever pivotally mounted in said support and having an inclined arm, means carried by said lever for securing one end of the yarn to be tested, means for securing the yarn at a fixed point, a weighted runner mounted to travel by gravity down the inclined arm of said lever, means for controlling the speed of travel of said runner, and means actuated by said lever for interrupting the travel of said runner.

3. In a machine for testing yarns, a support, a lever pivotally mounted in said support and having an inclined arm, means carried by said lever for securing one end of the yarn to be tested, means for securing the yarn at a fixed point, a weighted runner mounted to travel by gravity down the inclined arm of said lever, and means for controlling the speed and distance traveled by said runner, a scale attached to said lever, and a pointer carried by said runner and co-operating with said scale.

4. In a machine for testing yarns, a support, a lever pivotally mounted in said support and having an inclined arm, means carried by said lever for securing one end of the yarn to be tested, means for securing the yarn at a fixed point, a weighted runner mounted to travel by gravity down the inclined arm of said lever, and means for controlling the speed and distance traveled by

said runner, a scale carried by said support, and a pointer on one end of said lever and coöperating with said scale.

5. In a machine for testing yarns, a support, a lever pivotally mounted in said support, means carried by said lever for securing one end of the yarn to be tested, means for securing the yarn at a fixed point, a weighted runner mounted to travel on one 10 arm of said lever, and means for controlling the speed and distance traveled by said runner, a scale carried by said support, a weighted indicator member coöperating with said scale, a cord connected to said lever and suspending said weight, and a locking device adapted to engage said cord.

6. In a machine for testing yarns, a support, a lever pivotally mounted in said support, means carried by said lever for securing one end of the yarn to be tested, means for securing the yarn at a fixed point, a weighted runner mounted to travel on one arm of said lever, and means for controlling the speed and distance traveled by said runner, a scale carried by said support, a pointer on one end of said lever coöperating with said scale, a weighted cord connected with said lever, and a locking device adapted to engage said cord.

30 7. In a machine for testing yarns, a balance lever, bearings therefor, a gravity operated weighted runner mounted on one arm of said lever, a controlling device for said runner, a flexible connection between said

controlling device and said runner, said 35 bearings being provided with means for holding said flexible connection in alinement with said controlling device and said runner, and means for attaching the yarn to be tested to said lever.

8. In a machine for testing yarns, a balance lever, bearings for said lever, a weighted runner mounted on said lever, flexible connections to said runner, a spring actuated barrel upon which said flexible connections may be wound, a momentum governor mounted to act in conjunction with said barrel and means whereby the yarn may be attached to the balance lever, substantially as herein specified.

40 9. In a machine for testing yarns, a balance lever a weighted runner mounted on said lever, flexible connections for said runner, a winding drum around which the flexible connection is arranged to coil, devices for 45 arresting the motion of said drum on the breakage of the yarn, and means whereby the yarn may be secured to the balance lever and to a fixed body substantially as herein specified.

50 In testimony whereof I have affixed my signature in presence of two witnesses.
